CARL GARVIN, OF DAYTON, IOWA.

INTERLOCKING TILE-SECTION.

1,257,337.

Specification of Letters Patent. Patented Feb. 26, 1918.

Application filed February 21, 1917. Serial No. 156,925.

To all whom it may concern:

Be it known that I, CARL GARVIN, a citizen of the United States, residing at Dayton, in the county of Webster and State of Iowa, have invented certain new and useful Improvements in Interlocking Tile-Sections, of which the following is a specification.

This invention relates to improvements in interlocking tile sections and more particularly to reinforced arcuate tiles adapted to be assembled for forming relatively large conduits and similar cylindrical shaped devices.

The primary object of the invention is to provide a construction for an interlocking tile section of this character that will effectively reinforce the section and prevent collapsing and breaking of the section while undergoing heavy strains and stresses.

Another object of the invention is to provide a section having improved strengthening means adapted to act together when the sections are arranged in assembled position for forming a conduit so that increased strength is provided for the conduit without increasing the plate or quantity of material from which the same is constructed.

The above and additional objects are accomplished by such means as are illustrated in the preferred embodiment and in the accompanying drawings, wherein like characters denote like or corresponding parts throughout the several views, in which:

Figure 1 is a transverse section through a conduit showing a plurality of the tile sections in position.

Fig. 2 is a detail perspective view of one of the tile sections.

Referring particularly to Fig. 2 of the drawing, it will be observed that the section comprises an outer convexed wall 1 and an inner concaved wall 2 and these walls form the outer and inner walls, respectively, of the conduit when the tiles are assembled. The sides of the section are shaped to form the interlocking walls 3 and each of these walls includes the upper portion 4 which lies in a plane in radial alignment with the center of the conduit formed by the assembled sections. The lower portion 5 of each interlocking wall 3 is disposed at a sharper angle than the portion 4 and the two surfaces or portions 4 and 5 are joined by the steps 6 disposed in a circumferential plane and midway between the convexed wall 1 and the concaved wall 2.

The interior of the tile section is provided with the longitudinally extending truss walls 7, 8, 9 and 10 which are disposed at an angle for the purpose of strengthening the concaved and convexed walls without adding too much to the weight of the section or materially increasing the quantity of material from which the same is constructed. The walls 7 and 8 have their outer edges integrally formed with the inner surface of the convexed and concaved walls of the section. The meeting edges of the truss walls 7 and 8 are integrally connected together and also integrally formed with a brace tongue 11 which is carried by the proximate surface of one of the walls 3. This brace tongue is substantially wedge shaped in cross section and is disposed midway between the convexed and concaved walls so that its center is in alignment with the steps 6 thus preventing any weakness at the point where the steps 6 are formed in the side wall. The other two truss walls 9 and 10 are constructed in the same manner and are connected to the brace tongue 12 which is the counterpart of the brace tongue 11 at the opposite side of the tile. This tongue is also wedge shaped in cross section and prevents any weakness occurring in the wall 3 at the point where the steps 6 are formed.

Referring particularly to Fig. 1, wherein a plurality of the tiles are assembled together, it will be noted that the sides 3 are in engagement and are interlocked by virtue of the steps 6 and the angularly disposed surfaces 5 of the side walls. It is noted that the inward pressure of one of the tiles causes the strain to be received not only on the step 6 of the adjacent tile but the angular surface 5 also assumes some of the strain by reason of its angular disposition. Accidental crushing of the sections is prevented by the truss walls and they, in turn, are reinforced by the wedge shaped tongues 11 and 12 which also prevent a weak point occurring in the side walls where the steps 6 are formed. These steps also provide a sharp-corner-lock that is more efficient than the rounded tongue and curved lock often employed in devices of this character since the possibility of leakage is greatly reduced and the width of the steps can be increased without materially altering the construction of the tile.

From the foregoing it will be observed that a very simple and durable interlocking

tile section has been provided, the details of which embody the preferred form. I desire it to be understood however, that slight changes in the minor details of construction 5 may be made without departing from the spirit of the invention or the scope of the claims hereunto appended.

I claim:

1. An interlocking tile section comprising a convexed and a concaved wall, interlocking side walls joining the marginal edges of the convexed and concaved walls, steps formed in the interlocking side walls, truss walls interposed between the convexed and 10 concaved walls, the said truss walls being arranged in pairs having their meeting edges connected to the said side walls, the truss walls in each pair being disposed at an angle to each other, and having their meeting edges joined to the side walls in proximity to the said steps, and brace tongues formed at the point of juncture of the said truss walls with the side walls.
2. An interlocking tile section comprising a convexed and a concaved wall, interlocking side walls joining the marginal edges of the convexed and concaved walls, steps formed in the interlocking side walls, truss walls interposed between the convexed and 25 concaved walls, the said truss walls being arranged in pairs having their meeting edges connected to the said side walls, the truss walls in each pair being disposed at an angle to each other, and having their meeting edges 30 joined to the side walls in proximity to the said steps, brace tongues formed at the point of juncture of the said truss walls with the side walls, and disposed in central alignment with the plane of the said steps.

joined to the side walls in proximity to the 35 said steps, brace tongues formed at the point of juncture of the said truss walls with the side walls, the said brace tongues being of wedge shaped formation in cross section and disposed in central alignment with the plane 40 of the said steps.

3. In an interlocking tile section, the combination of convex and concaved walls disposed parallel and having interlocking side walls joining their marginal edges, the said 45 side walls being disposed radially with respect to the curved convex and concaved parallel walls, steps formed in the said interlocking side walls, obliquely disposed truss walls interposed between the said convex and concaved walls and having their 50 meeting edges integrally formed with the said walls, the said truss walls being arranged in pairs, each pair being disposed at an angle with respect to the other pair, the 55 truss walls in each pair also having meeting edges joined to the side walls in close proximity to the said steps, brace tongues formed at the point of juncture of the said truss walls with the side walls, and disposed in 60 central alignment with the plane of the said steps.

In testimony whereof I affix my signature in presence of two witnesses.

CARL GARVIN.
